US0D1075294S

(12) **United States Design Patent** (10) **Patent No.:** **US D1,075,294 S**
(45) **Date of Patent:** **** May 20, 2025**

(54) **CARD HOLDER**

(71) Applicant: **Gengxiao Zheng**, Jieyang (CN)

(72) Inventor: **Gengxiao Zheng**, Jieyang (CN)

(**) Term: **15 Years**

(21) Appl. No.: **29/982,974**

(22) Filed: **Jan. 8, 2025**

(30) **Foreign Application Priority Data**

Jul. 26, 2024 (EM) 015067767-0001

(51) **LOC (15) Cl.** **03-01**

(52) **U.S. Cl.**

USPC **D3/247**

(58) **Field of Classification Search**

USPC D3/201, 218, 247, 248, 249, 250, 251,

D3/303, 318, 203.3; D19/86; D14/435,

D14/436, 250

CPC A45C 1/06; A45C 1/10; A45C 11/182;

A45C 13/00; A45C 11/00; G09F 1/10;

H01F 7/0252

(57) **CLAIM**

The ornamental design for a card holder, as shown and described.

DESCRIPTION

FIG. 1 is a front perspective view of a card holder, showing my new design;

FIG. 2 is a rear perspective view thereof;

FIG. 3 is a top perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof; and,

FIG. 9 is a bottom view thereof.

The broken lines in the drawings illustrate the portions of the card holder, which form no part of the claimed design.

1 Claim, 9 Drawing Sheets
